United States Patent Office.

P. L. BUTLER, OF UTICA, NEW YORK.

Letters Patent No. 69,072, dated September 24, 1867.

IMPROVED REIN-SNAP.

The Schedule referred to in these Letters Patent and making part of the same.

TO WHOM IT MAY CONCERN:

Be it known that I, P. L. BUTLER, of Utica, county of Oneida, and State of New York, have invented a Rein-Snap; and I do hereby declare the following to be a full, clear, and exact description thereof, reference being had to the accompanying drawings, making part of this specification, in which—

Figure 1 is a perspective view of my improved rein-snap complete.

Figure 2 is a side view of the snap with a ring fastened to it.

Figure 3 is a similar view, showing the ring in the act of passing out between the inner snap-spring and the outer guard-spring.

Figure 4 shows the ring in the act of passing between the hook of the snap and the guard-spring thereof.

Similar letters of reference indicate corresponding parts in the several figures.

The object of this invention is to construct a very simple and cheap rein-snap, which shall afford a very safe fastening when attached to a ring or other object, and which shall admit of ready detachment from such object, when required.

The nature of my invention consists in the application to a hooked rein-snap of two springs, which are so arranged as to afford double security against the casual detachment of the snap from a ring or other object to which it may be attached, as will be hereinafter described and explained.

To enable others skilled in the art to understand my invention, I will describe its construction and operation.

In the accompanying drawings, A represents the oblong eye of the snap, by which it is attached to a rein. B is the shank of the snap, which terminates in a hook; C, having a curved point, a. At the junction of the shank B with its oblong eye A, two lips or flanges are formed on the sides of the former, between which two springs c d are riveted or otherwise secured. The raised lips on the sides of the shank of the snap are for affording lateral support for the two springs, and preventing their free ends from being turned out of line with their hook. The spring c extends beneath the point of the hook, where its end is curved inward, so that a ring, D, may be readily detached from the snap, by pressing it backward between the point of this spring and the bend of the hook, without having to press the spring inward with the fingers. This spring is designed to serve as a latch for retaining the ring within the space formed by it and the hook of the snap; but under some circumstances it has been found that a ring will work its way between the point of this spring and the hook, and allow of the detachment of the snap. The spring d is designed to serve as a guard to prevent the detachment of the snap from its ring should the latter escape past the spring c, and to this end the free end of the spring d presses upon the out-turned point of the hook C, and projects slightly beyond this point, as shown in the drawings.

Thus it will be seen that should the ring pass the spring c, and get between the two springs, the outer spring or guard will serve to prevent the snap from detachment from the ring; and, by having the point of the hook curved, as shown in the several figures of the accompanying drawings, a slight jerk or pulling of the snap and ring will bring the latter back within the hook, as shown in figs. 1 and 2. The object of projecting the point of the guard-spring d beyond its bearing upon the point of the hook is to allow of the ready attachment of a ring or other object to the snap without having to raise the spring d with the fingers.

It will be seen from the above description that the snap is attached to a ring by pressing these parts together, as shown in fig. 4, thus bringing the ring between the springs c d, and then drawing the ring back into the hook, as shown in figs. 1 and 2. These two movements are required for detaching the snap from its ring.

Having described my invention, what I claim as new, and desire to secure by Letters Patent, is—

A rein-snap, having two springs c d, or their respective equivalents, applied to it, so as to operate substantially as specified.

P. L. BUTLER.
